UNITED STATES PATENT OFFICE.

JOSEPH L. FIRM, OF CHICAGO, ILLINOIS, ASSIGNOR TO THE GOSS PRINTING PRESS COMPANY, OF CHICAGO, ILLINOIS.

PRINTING-MACHINE.

SPECIFICATION forming part of Letters Patent No. 701,699, dated June 3, 1902.

Application filed March 19, 1896. Serial No. 583,853. (No model.)

To all whom it may concern:

Be it known that I, JOSEPH L. FIRM, a citizen of the United States, and a resident of Chicago, in the county of Cook and State of Illinois, have invented certain new and useful Improvements in Printing-Machines, of which the following is a specification.

In the accompanying drawings, Figure 1 shows the printing mechanism constructed for printing in a single color on four webs. Fig. 2 shows the same constructed for printing on three webs and with two or more colors printed on the outside of one web. Fig. 3 shows the machine constructed for printing on two webs with four colors on the outside of one of them. Fig. 4 shows the folding mechanism detached. Fig. 5 is a vertical section in a plane through W' of Fig. 4. Fig. 6 shows a modification with the webs passing over the top of the carrier W W' instead of underneath, as shown in Fig. 5. Fig. 7 shows means for adjusting the carrier W or W' on the shaft w.

Fig. 1 described: Here are shown four printing mechanisms, one above another, with the cylinders of each arranged in a horizontal plane. A, B, C, and D are the four webs to be printed and associated between the rollers 5 6. The web A passes between the guide-rollers 1 and 2, thence between the impression-cylinder E and form-cylinder F, where it is printed on one side, thence between the impression-cylinder G and form-cylinder H, where it is printed on the opposite side, thence between the rollers 3 and 4, where it meets the web B. The web B passes around the guide-roller 9, thence between impression-cylinder I and form-cylinder J, where it is printed on one side, thence between impression-cylinder K and form-cylinder L, where it is printed on the opposite side, thence between the guide-rollers 3 and 4. The web C passes around guide-roller 10, thence between the impression-cylinder M and form-cylinder N, where it is printed on one side, thence between the impression-cylinder O and form-cylinder P, where it is printed on the opposite side, thence between the guide-rollers 11 and 12, where it meets the web D. The web D passes around guide-roller 15, thence be-

tween the impression-cylinder Q and the form-cylinder R, where it is printed on one side, thence between the impression-cylinder S and form-cylinder T, where it is printed on the opposite side, thence between the guide-rollers 11 and 12. From the guide-rollers 3 and 4 to the guide-rollers 5 and 6 the webs A and B pass in a direct line, one lying upon the other, to the rollers 5 and 6. After leaving the rollers 11 and 12 the webs C and D, one lying upon the other, pass between the guide-rollers 13 and 14 and thence in a direct path between the rollers 5 and 6, where they pass under the webs A and B and thence to the longitudinal folder. Each web is two pages wide, and each printing mechanism is adapted to print two pages abreast. I prefer to employ for folding the two inversely-arranged longitudinal folders U and V, so arranged as that both of them deliver the longitudinally-folded products onto the carrier W W'. By this arrangement and the arrangement of the guide-rollers 5 6 and 7 8, as shown in Figs. 1 and 4, I am enabled to deliver the webs onto the carrier W W', either collected so as to produce a single product of sixteen pages or so as to produce two products of eight pages each. When it is desired to produce a single product of sixteen pages, the longitudinal folder U is not used, and all four of the webs pass from the guide-rollers 5 6 over the longitudinal folder V, whereby three of the webs are folded inside of the fourth and delivered thus folded onto the carrier part W, by which they are all transversely folded inside of each other and cut transversely from the web, so as to deliver a completed product of sixteen pages. When it is desired to produce two products of eight pages each, both of the longitudinal folders U and V are employed. The webs A and B pass from the guide-rollers 5 and 6 between the guide-rollers 7 and 8 and are folded longitudinally inside of each other by the longitudinal folder U, from which they pass onto the carrier part W' to be transversely folded and cut and delivered thereby as a product of eight pages. The webs C and D pass from the guide-rollers 5 and 6 to the longitudinal folder V, by which they are longitudinally folded inside 100

of each other and delivered to the carrier part W, whereby they are transversely folded and cut and delivered as another product of eight pages. The dotted lines, Figs. 1, 2, and 3, 5 show alternative web-leads that may be adopted in lieu of those shown in full lines.

The folding mechanism shown in Fig. 1 is shown more in detail in Figs. 4, 5, and 6. 10 16 and 16' are the folding-rollers at the apex of the longitudinal folder U. 17 17' are the folding-rollers at the apex of the longitudinal folder V. The carrier part W and the mechanism for delivering therefrom is the same as the carrier part W', which is shown in Figs. 15 5 and 6. a a' are transversely-cutting knives which coöperate with a matrix in the roller 30. b and b' are pins to hold the forward end of the web, which pins are carried by the levers b² and b³, operated by the cams c and c', attached to the folding-blades d and d'. The construction and mode of operation of these parts need not here be described in detail, since it is fully described in my Patent No. 556,409, dated March 17, 1896. From the rollers 16 and 16' the webs pass between the carrier W' and the tapes 29 and remain on the carrier until the transverse margin between the pages is opposite the opening between the rollers 30 and 31, when they are driven off of the carrier between those rollers and pass between the tapes 35 and the stripper 36 to the carrier Y, where the successive cuts are gripped by the grippers 33 and 34 and delivered onto the table composed of the belts 37, 30 carried by the rollers 38, 39, 40, 41, 42, and 43.

The carrier parts W and W' in operation move as one part, being both fixed to the shaft w; but for purposes of adjustment they are made separate from each other and each is 40 loose upon the shaft and provided with a set-screw or other mechanical device whereby after it is rotated by hand upon the shaft to any desired position it may be fixed there. In this manner each of the carriers W and 45 W' may be set so as to receive properly the webs coming from its longitudinal folder, and when so set the two carriers will move together with positive accuracy. Each of the carriers may be adjustably secured to the 50 shaft w by means shown in Fig. 7, which consists of the cross-head w', keyed to the shaft w by key w² and slotted, so as to be adjustably secured to the carrier by the bolts w³ and w⁴.

55 Fig. 2 described: The machine shown in this figure is adapted for printing and associating three webs into a twelve-page paper, the outside of which is printed in two or more colors. B', C', and D' are the web-rolls. The 60 web B' passes around the roller 9, thence between the impression-cylinder I' and form-cylinder J', where it receives on one side the color blue, thence between the impression-cylinder E' and form-cylinder F', where it receives on the same side the color yellow, thence 65 over the guide-rolls 1 and 2, thence between

the impression-cylinder G' and form-cylinder H', where it receives on the same side the color red, thence past the guide-roll 17, thence between the impression-cylinder K' and form-cylinder L', where it is printed on the opposite side in any color, thence between the guide-rollers 3 and 4, thence to the collecting-rollers 5 and 6, where it meets the other webs. The webs C' and D' are printed in the 70 same manner as described for the webs C and D of Fig. 1 and conducted in the same manner to the guide-rollers 5 and 6, where they are associated with the web B'. From the rollers 5 and 6 all of the webs pass to the 75 longitudinal folder V' and are thereafter received by mechanism similar to that described in connection with Fig. 1. The printing mechanisms are arranged as shown in Fig. 1, excepting that the cylinders in the top row are 80 geared to be driven in the opposite direction by intermediate gears, as is well known.

Fig. 3 described: Here a similar arrangement of printing-cylinders to that shown in Figs. 1 and 2 is compounded for four colors, 90 using the webs C² and D². The web C² passes under the guide-roll 9, thence between the impression-cylinder I² and the form-cylinder J², where it is printed on one side in one color, thence between the impression-cylinder E² 95 and form-cylinder F², where it is printed on the same side in a second color, thence over the guide-rollers 1 and 2, thence between cylinders G² and H², where it is printed on the same side in a third color, thence between the impression-cylinder K² and form-cylinder L², where it is printed on the same side in a fourth color, thence around impression-cylinder O² and between it and form-cylinder P², where it is 105 printed on the opposite side, thence over guide-roll 18 and between guide-rolls 21, 22, and 23, where it meets the other web. The web D² passes over guide-roll 24, thence between impression-cylinder Q² and form-cylinder R², thence between impression-cylinder 110 S² and form-cylinder T², thence over guide-rolls 19 and 20 and between guide-rolls 21 and 23, where it meets the web C². Thence the two webs pass between the guide-rolls 5 and 6 to the longitudinal folder V'. 115

It will be observed that where the printing is done in superposed colors, as in Figs. 2 and 3, the colors are placed upon the outside of the outside web and continued on the outside when the webs are folded at the longitudinal folder V'. It will also be observed that in the printing mechanism shown in Figs. 1, 2, and 3 an inking mechanism is arranged at the end of each row, the inking-cylinders being lettered e f g h i j k l. The two upper 120 printing mechanisms in Fig. 1 show extra sets of fountain-rollers m and n, o and p, to be used when required for color-printing, the fountain-rollers q, r, s, and t being adjusted so as not to be in operation for color-printing, 125 but being adjusted so as to be in operation when not color-printing. I may also use, if 130

desired, turning-bars (shown at 50, Fig. 1) for turning the webs C and D as they pass from the rollers 13 14 to the rollers 5 6.

What I claim is—

- 5 1. In combination, a printing mechanism, two longitudinal folders U and V, two rotary carriers W and W' in axial alinement with each other and located in position to receive the paper from said longitudinal folders and
- 10 adjustable means whereby said rotary carriers may be fixed together at various circumferential adjustments with respect to each other, substantially as described.

2. In combination, a printing mechanism, two longitudinal folders, the folding-rollers 15 at the apices of said longitudinal folders, two rotary carriers in axial alinement and parallel with said folding-rollers and means whereby the circumferential position of said carriers may be adjusted relatively to each other, substantially as described.

JOSEPH L. FIRM.
